H. J. SHELTON

GRINDER AND PULVERIZER

Filed July 17, 1922

INVENTOR
Harry J. Shelton
By J. Henry Pinealy
ATTORNEY

UNITED STATES PATENT OFFICE.

HARRY J. SHELTON, OF ST. LOUIS, MISSOURI.

GRINDER AND PULVERIZER.

Application filed July 17, 1922. Serial No. 575,561.

To all whom it may concern:

Be it known that I, HARRY J. SHELTON, residing in the city of St. Louis, in the State of Missouri, have invented a new and useful

5 Improvement in Grinders and Pulverizers, of which the following is a full, clear, and exact specification, reference being had to the accompanying drawings, which form a part thereof.

10 My invention relates to grinders and pulverizers, and more particularly to grinders and pulverizers of a type in which the material to be ground or pulverized is passed between grinding rolls and a grinding ring.

15 In the use of a grinder and pulverizer of this character it is very common to feed too rapidly the material to be reduced, thereby overloading the machine; and it is also quite common for pieces of metal, rock, or other 20 hard substances to get in with the material being ground or pulverized. In both cases great harm is often done to the machine when either the overload of material or the hard, foreign substance passes between the 25 grinding rolls and the grinding ring. Several devices have been designed to allow the grinding rolls to kick back from the grinding ring when encountering an overload or a hard substance in the material being 30 ground, but it was found that such devices were not dependable and that some time a hard substance was wedged between the grinding roll and grinding ring, thereby bending the shaft upon which the grinding 35 roll was mounted or otherwise seriously injuring the machine.

The objects of my invention are to provide 40 means for mounting the grinding rolls in a grinder and pulverizer which will eliminate breakage of the grinding roll or damage to the machine under an overload of material to be ground or because a hard substance is in said material; to provide a means for mounting the grinding rolls in a grinder and 45 pulverizer whereby the rolls may kick back from the grinding ring when encountering an overload or material or a hard, foreign substance is in the material being reduced; and to provide a resilient means for mounting 50 the grinding rolls in a grinder and pulverizer which will facilitate the adjustment of said rolls in relation to the grinding ring.

55 My invention is fully shown in the accompanying drawings wherein similar numerals are used to designate similar parts. Fig. 1 is a side elevation of a grinder and pulver-

izer embodying my invention; Fig. 2 is a section along the line 2—2 in Fig. 1; and Fig. 3 is a view partly in section showing more clearly details of construction of the 60 resilient means for holding the grinding rolls to bear against the grinding ring.

Referring to the figures, the grinder and pulverizer has a housing formed by a main casting 1 with the hopper 25 at the top 65 thereof into which material to be reduced is placed and from which the material is passed through a discharge pipe, not shown, into the inside of the grinding ring. A side casting 2 is hinged to the main casting on the pintle 3 passing through the extensions 3^a and 3^b from the castings 1 and 2, respectively. The side casting 2 is, preferably, maintained in position on the casting 1 by means of the bolts 4 passing through 70 the lugs 5, as shown in Fig. 2. The grinding ring 6 is fastened to the back plate 7 by means of the bolts 8 and both the grinding ring 6 and the plate 7 are mounted on the drive shaft 9 so as to be rotated thereby. 75 The drive shaft 9 is revolvably mounted so as to extend through the vertical rear wall of the main casting 1 and the large nut 10 threaded on the end of the shaft 9 holds the grinding ring in place thereon. The grinding 80 rolls 11 are, preferably, journaled on the shaft 12 extending from the arm 13 and are adapted to bear against the inner or grinding surface of the grinding ring 6. The grinding rolls are, preferably, convex, so as 85 to conform to the concave contour of the grinding ring, as shown in Fig. 2.

By placing the pair of grinding rolls 11 so that they contact with the grinding ring 6 at points thereon that are substantially 90 diametrically opposite each other, as shown on the drawings, the pressure of the rolls on the ring does not tend to twist the ring shaft 9 in its bearings and thereby undue friction 95 of the shaft in the bearings is avoided. This positioning of the rolls with respect to the grinding ring insures also that substantially all of the strain due to the pressure of the rolls 11 is taken up by the ring and not by 100 the bearings of the shaft 9.

105 The resilient means for holding the grinding rolls against the grinding ring is constructed as follows: The wrist 14, formed at and preferably made integral with one end of the arm 13, is mounted in the bearing 15. 110 The clevis 16 is swingably attached to the end of the arm 13 opposite the end having

the wrist 14 formed thereon. The shaft 12 extends from the arm 13 between the clevis 16 and the wrist 14. The shank end 16^a of the clevis 16 has a socket therein adapted to receive the end of the unthreaded end of the bolt or rod 17. The rod or bolt 17 is threaded for the greater portion of its length from the head towards the end, but the portion adjacent its end is unthreaded and reduced 10 in diameter to form the shoulder 18. The washer 19 in engagement with the shoulder 18 is in contact with one end of the coil spring 20 and the other end of the spring 20 is in contact with the face of the clevis 16 15 at the base of the shank 16^a, as shown in Fig. 3. The block 21 with the pins 22 at either side thereof is threaded upon the rod 17. The block 21 is adapted to lie in the recess 23 formed in a boss 24 integral with the side 20 casting 2 of the housing, with the pins 22 engaging in notches 23^a formed in the walls of the recess 23.

The spring 20 expanding between the washer 19, which is held immovable by the 25 shoulder 18, and the face of the clevis 16 holds the arm 13 outwardly, thereby maintaining the grinding roll 11 in proper relation with the grinding ring 6. If the machine is overloaded or a hard substance is in 30 the material being ground or pulverized, the grinding roll is allowed to kick back from the grinding ring when the strain of such overload or hard substance transmitted through the arm 13 is sufficient to compress the 35 spring 20. The compression of the spring 20 and, in turn, the relation between the grinding roll 11 and the grinding ring 6 may be regulated by turning the rod 17 in the block 21. If the grinding roll is to 40 bear harder against the grinding ring the screw shaft is turned so that the washer 19 moves towards the clevis 16 thereby compressing the spring. The recess 23 is 45 slightly larger than the block 21, so that the screw shaft 17 may pivot slightly on the pins 22 as an axis to allow for the change in angle between the screw shaft and the arm 13 when said shaft is turned in adjusting the rolls 11 in relation to the grinding 50 ring 6.

As the grinding ring 6 is revolvably carried by the main casting 1 and as the grinding rolls 11 and the means for holding these grinding rolls in grinding relation against 55 the grinding ring 6 are carried by the side casting 2, all as described above, the bolts 4 may be withdrawn from the lugs 5 and the side casting may be swung around on the pintle 3 out of operative position on said 60 main casting, to carry the grinding rolls 11 out of engagement with the grinding ring 6. This construction allows easy access to the housing whereby the grinder and pulverizer may be repaired, cleaned or adjusted.

I do not propose to limit myself to the exact construction of the parts shown in the drawings since it may be clearly understood that the shape of many of the parts and particularly the method for pivotally mounting the arm 13, the means for adjusting the shaft 17 and the form of spring used may be varied within a wide range without deviating from the spirit of my invention.

What I claim as new and desire to secure by Letters Patent, is:

1. In a grinder and pulverizer having a housing comprising a main casting with a grinding ring rotatably mounted therein and a side casting hinged to said main casting, a pair of grinding rolls rotatably mounted to contact with the inner surface of said grinding ring at substantially diametrically opposite points thereof, each of said grinding rolls having associated therewith a shaft upon which said roll is mounted, an arm pivotally mounted on said side casting and carrying said shaft, resilient means mounted on and carried by said side casting for engaging said arm to cause its associated grinding roll to be held normally in grinding relation with said grinding ring.

2. In a grinder and pulverizer having a housing comprising a main casting with a grinding ring rotatably mounted therein and a side casting hinged to said main casting, a pair of grinding rolls rotatably mounted to contact with the inner surface of said grinding ring at substantially diametrically opposite points thereof, each of said grinding rolls having associated therewith a shaft upon which said roll is mounted, an arm pivotally mounted on said side casting and carrying said shaft, resilient means pivotally mounted on and carried by said side casting for engaging said arm to cause its associated grinding roll to be held normally in grinding relation with said grinding ring.

3. In a grinder and pulverizer having a housing comprising a main casting with a grinding ring rotatably mounted therein and a side casting hinged to said main casting, a pair of grinding rolls rotatably mounted to contact with the inner surface of said grinding ring at substantially diametrically opposite points thereof, each of said grinding rolls having associated therewith a shaft upon which said roll is mounted, an arm pivotally mounted at one end on said side casting and carrying said shaft, adjustable resilient means mounted on and carried by said side casting for engaging the free end of said arm to cause its associated grinding roll to be held normally in grinding relation with said grinding ring.

4. In a grinder and pulverizer having a housing comprising a main casting with a

- grinding ring rotatably mounted therein and a side casting hinged to said main casting, a pair of grinding rolls rotatably mounted to contact with the inner surface of said 5 grinding ring at substantially diametrically opposite points thereof, each of said grinding rolls having associated therewith a shaft upon which said roll is mounted, an arm pivotally mounted at one end on said 10 side casting and having said shaft mounted thereon intermediate the ends thereof, adjustable resilient means pivotally mounted on and carried by said side casting for engaging the free end of said arm to cause its associated grinding roll to be held normally in grinding relation with said grinding ring. 15

In witness whereof I have signed my name to this specification.

HARRY J. SHELTON.
